DESIGN FOR A BRUSH HANDLE

Application filed August 12, 1929. Serial No. 32,391. Term of patent 14 years.

To all whom it may concern:

Be it known that I, WILLIAM J. TREVILLIAN, a citizen of the United States, residing at Freeport, county of Stephenson, State of Illinois, have invented a new, original, and ornamental Design for Brush Handle, of which the following is a specification, reference being had to the accompanying drawing, forming a part thereof.

The figure is a perspective view of a brush handle, showing my new design.

The dominant feature of the design is the arrangement of the elongated longitudinally extending facets in combination with the disposition of the relatively shorter facets on the shoulder and the provision of the smooth intermediate neck portion setting off the faceted portions.

I claim.

The ornamental design for a brush handle, as shown and described.
